UNITED STATES PATENT OFFICE.

SAMUEL GUTH, OF WASHINGTON, ILLINOIS.

PORTABLE GRAIN-DUMP.

SPECIFICATION forming part of Letters Patent No. 760,862, dated May 24, 1904.

Application filed January 4, 1904. Serial No. 187,744. (No model.)

To all whom it may concern:

Be it known that I, SAMUEL GUTH, a citizen of the United States, residing at Washington, in the county of Tazewell and State of Illinois, have invented certain new and useful Improvements in Portable Grain-Dumps; and I do hereby declare that the following is a full, clear, and exact description of the invention, which will enable others skilled in the art to which it appertains to make and use the same.

This invention pertains to portable grain-dumps, and has for one of its objects to produce an easily and freely operated grain-dump for unloading wagons.

It further relates to a combined grain dump and elevating device by which the grain emptied from the wagon can be elevated to any desired receptacle.

The invention also relates to certain details of construction, as will be pointed out in the specification and in the accompanying claims.

In the annexed drawings, Figure 1 is a side elevation of my improved grain dump and elevator. Fig. 2 is a plan view thereof. Fig. 3 is a detail view of a clutch mechanism for raising the wagon to be unloaded. Fig. 4 is a detail view in elevation of a driving-gear for a drag or conveyer into which the contents of the wagon is dumped. Fig. 4^a is a front view of a yoke employed on the conveyer shown in Fig. 4. Fig. 5 is a side view of a portion of the head of the elevator, showing adjusting means for a conveyer-shaft. Fig. 6 is a perspective view of an adjustable member shown in Fig. 5. Fig. 7 is a perspective view of means for carrying the front wheels of the wagon.

A indicates the platform of the dump, consisting of the usual sills and flooring and end approaches, the latter being indicated by B B. At one side of the platform a framing is extended, consisting of the beams C C. Mounted across these said beams in suitable bearings is a shaft D, forming a pivot for and driving means for an elevator E, whose lower extremity lies between said beams C C, as shown. The elevator is provided with the usual chains and drags, all of which are too well known to require more description here. Pivoted

to each beam C is an upright F, one being at 50 each side of the elevator, the upper ends approaching each other and carrying a grooved pulley G, over which runs a rope or cable, one end of which is connected to a bail H toward the head of the elevator, the other end passing around a windlass-roller I on a shaft J, mounted on the elevator. On the same shaft is a ratchet-wheel K, while a pawl L is carried on the side of the elevator in engagement with said ratchet, and it will be 60 seen that by turning the windlass by means of its crank the head of the elevator may be raised or lowered, as desired, the arms F acting as the support therefor. Said arms are slotted, and a clamping-screw is provided at 65 M, by which when the elevator is placed in the desired position can be secured. Overhanging the elevator-boot is a drag or conveyer N, which extends over the platform across the driveway, as indicated in Fig. 2. 70 Said conveyer is pivotally carried at its end adjacent to the elevator. In Fig. 1 is an upright O, secured rigidly by means of a brace P. Bolted to O is a casting Q, carrying a vertical shaft R, Fig. 4, whose upper end is 75 embraced by means of a boss S of a yoke T, Fig. 4^a. Beneath said boss the said shaft carries a gear-wheel U, which meshes with a gear-wheel V, serving to operate the drag-belt W of the conveyer, all of which is common to 80 machines of this class. The lower end of the shaft R carries a beveled gear X, which meshes with a similar wheel Y on a shaft Z, whose one end rests in a socket 2 of the casting Q, Fig. 4, its opposite end being carried 85 in a bearing 3 on one of the beams C. The outer end of said shaft Z is provided with a sprocket-wheel 4 for engaging with a similar wheel 5 on the shaft D by means of a chain 6, Figs. 1 and 2. Thus mounted the conveyer 90 may be swung around to the position shown in broken lines in Fig. 2, so that a wagon may be driven upon the platform for unloading. The beveled gears will easily permit said conveyer to be swung as described, since the upright ones will travel upon the horizontally-placed gears. If desired, a suitable support 95 may be placed at the free end of the conveyer

by which to hold that member from sagging and straining the gears and other parts at the pivoted end, all of which will be understood.

I now provide means for raising the front end of the wagon. This means consists, first, of a vertically-movable support for the front wheels. This said support is composed of two planks 7 and 8 of the platform, having beneath their ends blocks 9, said planks being hinged to the blocks, as shown at 10 in Figs. 1 and 7. The blocks are notched beneath the planks, as shown in Fig. 1, so that said planks will lie therein to thus form a depression in which the wheels will rest, as shown in broken lines in said Fig. 1. A yoke or bail 11 serves to support each block and is supported loosely from the end of a lever 12 to an upright 13 at each side of the platform. Pivoted at one end to said upright 13 is a rod 14, whose other end is suitably pivoted to said block 9, the purpose of which will presently appear. The free ends of the levers 12 loosely carry pulleys 15, through which runs a cable 16, one end being attached to the platform and the other end passing around a winding-drum 17 on a shaft 18, let into the planks of the platform, so as not to interfere with the driving of a wagon upon said platform. Said shaft 18 at one end is provided with a sprocket-wheel 19 and a ratchet-wheel 20, the latter being normally held from revolution by means of a pawl 21, pivoted on the platform and controlled by a pull-rod 22. The said sprocket-wheel 19 is connected by a chain 23 to a sprocket-wheel 24 on the shaft D, before described. The latter sprocket-wheel is secured to a sleeve 25, Fig. 3, carrying a portion of a friction-clutch 26, adapted to engage the drum 27 of such clutch, keyed at 28 to said shaft D. Said sleeve 25 also carries a shifting ring 29, operated by means of a forked lever 30. The shaft D is driven by means of a pulley 31 and during constant revolution drives only the conveyer through the sprocket-chain 6 described. The sleeve 25, above described, being loose on said shaft D does not move until shifted toward the drum 27, which, as before explained, is fast on said shaft D. When shifted toward and into 27, the sprocket 24 is revolved, thus imparting movement to the shaft 18 to wind up the cables. When this takes place, the levers 12 are drawn down by means of the cables 16, thereby raising the opposite ends of said levers and raising the planks 7 and 8 described. When the said planks 7 and 8 are at rest, they appear as shown in Fig. 1, where they rest upon the beams of the platform. Now when raised the planks by gravity fall into the notches of the blocks 9, thus, as before explained, forming a lodgment for the wheels of the wagon. It is evident that if the wheels were raised in a perfectly-vertical line the rear end of the wagon would necessarily be moved on its wheels first backward and then forward as the front wheels approach and pass

a horizontal line passing through the center of the axle of the rear wheels; but since the levers 12 are pivoted behind the wheels, which they raise, said wheels will describe an arc in their upward movement which practically is 70 described from said rear axles, and in this way the said rear end of the wagon will remain in one position while in the act of dumping, except a pivotal one on its axles. In order to guide the blocks 9 in these movements, the 75 said rods 14 are provided, and these serve to hold the blocks and planks horizontal and likewise answer to guide said blocks back between the under beams of the platform. At 32 is a hopper which is attached to the conveyer and 80 adapted to receive the contents of the wagon. Also at 33 is designated a hopper at the opposite side of the conveyer, into which grain may be dumped from various receptacles when desired for other purposes than a grain-dump 85 for wagons. In order to make the dump portable, I provide a pair of wheels 34, which may be placed beneath the platform after raising one end thereof.

At the head of the elevator the shaft 35 is 90 extended beyond the said head and carries a beveled gear 36, with which meshes a similar gear 37 on a stub-shaft 39, having a bearing in a yoke 38, through which said shaft 35 also passes. Said yoke is slotted, as shown in Fig. 95 6, and clamped to the elevator-head by means of a bolt 40 in Fig. 5, so that any adjustment of the yoke may be had. The purpose of this is that a conveyer may be driven by means of the shaft 39, and in order that said shaft may 100 be held horizontally at all times while the elevator is inclined at any height desired the yoke must be movable to permit said shaft 39 to be horizontal.

After raising the wagon to dump it, as described, it is only necessary to liberate the ratchet-wheel by withdrawing the pawl therefrom by means of the pull-rod 22 to permit the wagon to descend to its position for driving off of the platform, the clutch having 105 been disengaged during or before the dumping action takes place. The said clutch may of course be held in engagement, so as to gradually raise the wagon as the grain passes therefrom, or may be used to elevate the wagon 110 at once and then let the grain pass out as desired.

A point of advantage in my dump is the ease with which the carrying-wheels can be placed under the platform or removed therefrom. This is accomplished by the aid of the levers 12, together with two portable posts 41. These latter are set upon the ground immediately beneath the said levers 12 when it is desired to raise the platform to place the 115 wheels in position. One of them is inserted between one of the beams C and the side of the platform, while the other is let down through an aperture near the opposite side of the platform at 41^a. Now it will be seen that 120

in drawing down the levers they will rest upon these posts 41, and a continued winding of the cables 16 will result in raising the conveyer end of the platform, while the opposite end 5 rests upon the ground. The wheels can then be inserted or removed, as the case may be. The posts 41 are then removed and placed where they can be used at a moment's notice. It is to be understood, however, that any stick 10 sufficiently strong can be employed in lieu of the posts, as shown.

Again, returning to the yoke 38 and its parts at the head of the elevator, the shaft 39, journaled therein, carries a sprocket-wheel 15 42, which by means of a sprocket-chain 43 drives a sprocket-wheel 44 on a conveyer 45, hung beneath the head of the elevator and into which the grain can be discharged. This conveyer is also shown in broken lines in Fig. 2. 20 This construction is employed when it is impossible or inconvenient to get near the receptacle into which the grain is to be discharged, and it will be seen that with the said conveyer any remote place can be readily 25 reached.

I do not wish to confine myself to the particular construction and arrangement of parts described and shown, as various changes may be made without departing from the spirit of 30 the invention.

I claim—

1. In a portable grain-dump of the character described, a platform for supporting the wagon to be unloaded, removable carrying-wheels therefor, a drag for receiving the contents of the wagon, an elevator for receiving the grain from the conveyer, means for adjusting the elevator for height, means for supporting the front wheels of the wagon, levers 35 pivoted above the platform, the said latter means being connected therewith and other means for lowering the levers at one end to raise the said wheel-supporting means with the other ends substantially as set forth.

40 2. In a portable grain-dump, the platform, removable carrying-wheels therefor, a drag and elevator mounted on the platform, means for supporting the front wheels of the wagon, levers pivoted above the platform and having 45 the said means attached thereto and winding means for depressing the opposite ends of the levers for raising said means for the purposes set forth.

50 3. In a portable grain-dump, the platform, removable carrying-wheels therefor, a drag and elevator mounted on the platform, means for supporting the front wheels of the wagon to be unloaded, levers pivoted on the platform and having the said means connected therewith at one end, and means for depressing the opposite ends of the levers for raising the said wheel-supporting means for the purposes described.

55 4. In a portable grain-dump, the platform thereof, carrying-wheels therefor, a drag and

elevator mounted on the platform substantially as set forth, means for supporting the front wheels of the wagon and means for raising said supporting means consisting of levers pivoted rearward of the said supporting means 70 and having such means attached to the forward free ends, a winding-shaft journaled on the platform a cable adapted to wind thereon and also adapted to depress the rear ends of the levers for raising the said wheel-support for 75 the purposes set forth and described.

5. In a portable grain-dump, a platform for the vehicle to be unloaded, a conveyer and elevator for receiving the grain from the vehicle, manually-operated means for changing the 80 height of the elevator, a pivotal mast on the platform, a single cable attached to the upper end of the elevator and running over the mast, the latter means being carried on the said elevator substantially as shown. 85

6. In a portable grain-elevator, a platform for the wagon to be unloaded, a drag and elevator thereon for receiving and carrying away the grain and a vertically-operated support for the front wheels of the wagon, said support adapted to partially collapse to form a rest for the wagon-wheels when raised from the platform but regaining its normal level position when returned to said platform. 90

7. In a portable grain-elevator, a platform 95 for the wagon to be unloaded, a drag and elevator mounted thereon for the purposes indicated, a support for the front wheels of the wagon, said support lying flush with the floor of the platform and perfectly level as shown, 100 said support adapted to be raised to raise the wagon at its front end and also adapted when raised to partially collapse to form a rest for the wagon-wheels as set forth.

8. In a portable grain-dump, a platform for 105 the wagon to be unloaded, a drag and elevator for receiving and carrying away the grain, a support for the front wheels of the wagon, said support constituting a portion of the platform, means for raising said support to raise 110 the wagon on the support adapted to partially collapse substantially as described for forming a rest for the wheels of the wagon.

9. In a portable grain-dump, a platform for 115 the wagon to be unloaded, a drag and elevator therefor for the purposes set forth, a vertically-movable support for the front wheels of the wagon, the same comprising blocks notched in their upper surfaces, planks hinged to said blocks and adapted to drop into the notches 120 to form a rest for the said wheels only when raised above the platform, said planks being held level when in their normal position, and means for raising the support consisting of levers to which the support is attached, said 125 levers being pivoted above the platform, and winding mechanism for depressing the opposite ends of the levers all substantially as set forth and for the purposes described.

10. In a portable grain-dump, the platform 130

A, the conveyer N, the elevator E, the support consisting of the blocks 9 notched on their upper surfaces, the planks 7 and 8 hinged thereto, the lever 12 at each side of the platform, pivoted between their ends and carrying the said support at one end, the shaft 18, the drums 17 thereon, the cables 16 adapted to be wound on the drums for drawing down the levers, and means for driving said shaft 18 for the purposes described.

11. In a portable grain-dump, the platform thereof, a vertically-movable support for the front wheels of the vehicle, a pair of levers from which said support is suspended and by 15 which it is raised, means for raising the levers by drawing down the free ends thereof, said levers also adapted for tilting the entire platform for the purposes described.

12. In a portable grain-dump, a platform for 20 the wagon to be unloaded, a drag, an elevator, a raisable support for the front wheels of the wagon, levers pivoted above the platform for raising the support, means for operating the levers, operating mechanism for the drag and

elevator and devices between the said mechanism and the lever-operating means for raising the wagon-support at will while the drag and elevator are in constant motion. 25

13. In combination with a portable grain-dump and its elevator, a conveyer at the head 30 of said elevator for the purposes indicated, a yoke 38 carried on the elevator-shaft 35 and adapted to pivot around said shaft, said yoke being adjustably secured to the elevator, means for securing the yoke in stationary manner a 35 shaft 39 carried by said yoke at right angles to the said elevator-shaft 35 and means between both the shaft 39 and the shaft of the conveyer beneath, the said yoke 38 being adjustable to keep the shaft 39 horizontal without reference to the angle of inclination of the elevator. 40

In testimony whereof I affix my signature in presence of two witnesses.

SAMUEL GUTH.
